UNITED STATES PATENT OFFICE.

JOHN W. VAUGHN, OF JERSEY CITY, NEW JERSEY.

AUTOMATIC SELLING-MACHINE.

SPECIFICATION forming part of Letters Patent No. 407,946, dated July 30, 1889.

Application filed July 13, 1888. Serial No. 279,905. (No model.)

To all whom it may concern:

Be it known that I, JOHN W. VAUGHN, of Jersey City, county of Hudson, State of New Jersey, have invented certain new and useful 5 Improvements in Automatic Selling-Machines, of which the following is a specification.

This invention relates to improvements in the apparatus known as "automatic selling-machines," and in which goods are automatically delivered in exchange for a coin of certain value placed in the apparatus by the purchaser.

The object of my invention is to provide a new and improved machine or apparatus of this kind, which is so constructed that with a single motor or operating device various kinds of goods or various goods of the same kind, but of different values, will be automatically delivered.

20 The invention consists in a coin-chute head, in a detector for spurious coins, and in the construction and combination of parts and details, as will be fully described and set forth hereinafter, and pointed out in the 25 claims.

In the accompanying drawings, Figure 1 is a vertical transverse sectional view of my improved selling-machine on the line $x^9 x^9$, Fig. 2. Fig. 2 is a sectional plan view of the same 30 on the line ww , Fig. 1. Fig. 3 is a vertical longitudinal sectional view on the line xx , Fig. 1. Fig. 4 is a front elevation of the ball-releasing device, parts being in section. Fig. 5 is a side view of the parts shown in Fig. 4, parts 35 being in section. Fig. 6 is an elevation of a releasing device made adjustable for different numbers of coins. Fig. 7 is a side view of the construction shown in Fig. 6, parts being in section. Fig. 8 is a vertical longitudinal 40 sectional view of the mouth-piece for the coin-chute on the line $x^7 x^7$, Fig. 9. Fig. 9 is a sectional view of the same on the line $x^6 x^6$, Fig. 8. Fig. 10 is a rear view of the coin-chute, parts being in section.

45 Similar letters of reference indicate corresponding parts.

On the shaft A, journaled in the rear wall of the case or box A', and in a suitable arm A², the wheel B is mounted rigidly, which is provided in its rim with pockets B' for receiving balls B². A rope-drum A⁸ is fixed on the shaft A, on which the rope A⁴ is wound,

and from the same is suspended a weight A⁵, and a ratchet and pawl A¹² are provided for rotating the wheel B from the rope-drum, all 55 as is fully described in my application, Serial No. 277,087, filed June 14, 1888, for an automatic selling-machine. The wheel B has parts of its rim surrounded by curved shields B³ and B⁴ for the purpose of preventing the 60 balls from dropping out of the pockets B'. At the lower end of the shield B⁴ the chute B⁵ is provided, into which the balls pass as soon as their pockets are below the lower end 65 of the shield B⁴.

From the chute B⁵ the balls pass into the chute B⁶ at right angles to the chute B⁵, and from the lower end of said chute B⁶ they pass into the inclined chute B⁷, which is some distance in front of the wheel B, said chute 70 B⁷ being provided with a partition B⁸ near its lower end to prevent the balls rolling out. From the chute B⁷ a series of short guide-tubes C project downward at an inclination, their upper ends being so arranged that the 75 balls, when they arrive at said guide-tubes, can roll down the same and can drop into a box C', of which one is provided below each guide-tube, each box being provided at its 80 bottom with an outlet-tube C² for conducting the ball into a chute C³, located below the chute B⁷ and inclined in opposite direction.

From the lower end of the chute C³ the balls pass into the chute C⁴, and from the lower end of the same through a chute C⁵ into the 85 chute C⁶, the lower end of which is adjacent to the bottom part of the wheel B, so that said balls can pass from the chute C⁶ into the pockets B'.

It is necessary that the wheel B shall be rotated the distance of one pocket every time a ball drops into the chute C⁶, the weight acting on the rope-drum on the shaft A of the wheel B' furnishing the necessary power for rotating said wheel and elevating the balls. 90 As the balls pass through the chute C⁶, they act upon the arms of the spider-wheel C⁷, projecting into said chute, which spider-wheel C⁷ is connected with the wheel C⁸, having pins C⁹, that act on the lower end of the 100 pawl C¹⁰, the upper end of which engages teeth of a ratchet-wheel C¹¹ on the rim of the wheel B', so that every time a ball passes through the chute C⁶ the pawl C¹⁰ will be dis-

engaged from one tooth of the ratchet-wheel C¹¹ and permit the wheel B to rotate the distance of one pocket, there being as many teeth in the ratchet-wheel C¹¹ as there are 5 pockets B' in the wheel B.

I have shown three guide-tubes C connected with the chute B'; but, if desired, only one such guide-tube, or two, or more than three, may be provided, according to the various different kinds of articles to be sold by the machine, or according to the various goods of the same kind of article to be sold by the machine. For each outlet-tube C on the chute B', I provide a coin-chute and ball-releasing device operated by the coin passing through the coin-chute, and for each outlet-tube C a separate delivery-chain is to be provided, only one of which is shown, each of which chains is operated by a separate weight mechanism whenever a coin has been dropped or placed into the corresponding coin-chute, and also a separate outlet for the article delivered by each chain. As all the chains are alike and each chain is provided with a coin-chute-releasing device, &c., I will describe one only. The chain D and its connecting-band D⁸ are passed over a series of polygonal sprocket-rollers D' in different parts of the casing, as shown in Fig. 1.

30 The sprocket-rollers D' at the front of the boxes are each provided with a drum E, upon which a rope E' is coiled and passed over guide-pulleys E³, a weight E⁴ being suspended from the lower end of said ropes, and said 35 weight serving to operate or drive the corresponding box-link delivery-chain.

On the outer surface of one polygonal end disk of each front sprocket-roller D' an escapement-wheel F is secured, with the teeth 40 of which the escapement-fork F' can engage, that is mounted to rock on the shaft F² behind said wheel D'. Said escapement-fork F' has a bent arm F³, the lower end of which projects through a slot into the bottom part of 45 the box C', so that the balls dropping into said box can depress the lower end of said arm F³, thereby operating the escapement-fork. To insure the quick and rapid operation of the escapement, one shank of the fork is provided 50 with a weight F⁴. Diagonally below and in front of the front guide-roller D' the inclined chute G is provided, down which the article delivered slides and is dropped into a trough G' on the front of the casing, from which trough 55 it can readily be taken by the purchaser. The coins placed into the mouth-piece of the coin-chute (that will be described hereinafter) pass through the coin-chute H and drop into the funnel H', from which a chute H² leads to the 60 money drawer or tray H³. In case the coins deposited by the purchaser—for example, if a cent is deposited in place of a five-cent nickel it drops from the chute H into the chute H⁴, and from the same slides through 65 the chute H⁵ into the trough G', the chute H being inclined laterally and provided with a longitudinal slot in its side, as described in

my application Serial No. 277,087, filed June 14, 1888.

A lever I is pivoted on each guide-tube C 70 and has one end I' curved and projected into the upper end of the chute H², the curved end of said lever having about the same radius as the coin that has to be deposited. On the opposite end of said lever I a toe I² is provided 75 that can engage a pin I³ on the rim of a disk I⁴, mounted on a shaft I⁵, journaled in brackets on the under side of the guide-tube C. On said shaft I⁵ a spider-wheel J is fixed, which has as many arms J' as there are pins 80 I³ on the rim of the disk I⁴, or in some cases as many arms as there are groups of pins on the rim of said disk I⁴. In case the articles are to cost but a single coin—for instance, a five-cent nickel—the pins I³ are arranged 85 singly on the rim of the disk I⁴; but where the article is to cost two or three nickels the pins are arranged in groups of two or three nickels, and so on. The arms J' project through a longitudinal slot in the bottom of 90 the guide-tube C into said guide-tube. In some cases it is desirable to have the machine adjustable, so that it can be made to work for one, two, three, or more nickels. This construction is shown in Figs. 6 and 7, in which 95 four circumferential rows of pins I³ are provided on the disk I⁴. In one circumferential row the pins are arranged singly, in the next in groups of two, in the next in groups of threes, in the next in groups of fours, and 100 so on.

The disk and wheel J are fixed on a sliding sleeve I⁶, mounted to turn on its shaft and connected with a pivoted shifting-lever I⁷, the upper end of which is provided with a handle I⁸, that can be adjusted on a scale I⁹, (marked 1, 2, 3, 4, &c.,) so that by shifting the upper end of said lever the disk I⁴ can be so adjusted that the toe I² on the inner end of the lever I will be in the path of the circumferential row of pins, having single pins or groups of two or three, as may be desired.

It very frequently occurs that attempts are made to force banana-peels, pieces of paper, and like materials into the coin-chutes; and 115 to prevent this I have devised a mouth-piece (shown in Figs. 8 and 9) for the coin-chute. The top plate K of said mouth-piece is provided with an opening K', the inner edge of which is of the size of a five-cent nickel and 120 the outer part of which is flared. To the inner side of said top plate K a gate L is hinged, which is pressed outward and against the inner surface of the top plate by a suitable spring L'. Said top plate is provided with 125 three or more radial slots or notches M, in which sliding steel jaws M² are pressed against the rim of the gate by springs M³, secured in the shell or casing M⁶ of the mouth-piece. Said jaws are also provided with bevels M⁴ 130 above the outer surface of the mouth-piece and projecting beyond the inner edge of the opening K'. As the sliding jaws M² engage the edges of the gate, they keep said gate

closed and prevent its being pressed inward. When the coin is placed into the opening K' of the top plate K and pressed toward the upper surface of the gate L, the edges of said 5 coin, acting on the bevels M⁴ of the jaws M², press said jaws simultaneously in the direction from the center of the mouth-piece, whereby the edges of the gate are disengaged from said jaws, thus permitting the gate to be 10 swung inward. The coin then slips off the gate and drops into the V-shaped guide-chute N, by which it is placed on edge, and slides from the same to the coin-chute H. The spring L', which must have more power than 15 the springs M³, forces the gate outward and presses its edges against the bottom bevels M⁵ of the jaws M², whereby said jaws are pushed back sufficiently to permit them to lock the gate L in place.

20 The operation is as follows: The box-links D² of the chain D are filled, for example, with cigars, a cigar or a package of two, three, or more cigars being placed in each box-link, according as a single cigar or a package of 25 cigars is to be delivered each time a coin is deposited. In case there are three different chains, five-cent cigars could be placed in the box-links of the first chain, ten-cent cigars in the box-links of the second chain, and a 30 package of five-cent or ten-cent cigars in the box-links of the third chain, and so on. While successively filling the box-links in a chain said chain is moved in the direction of the arrow x², Fig. 1, whereby the ropes E' are 35 wound upon the drums E, and the weights E⁴ are thus raised. All the pockets of the wheel B are filled with balls, with the exception of those between the bottom of the shield B⁴ and the point at which the balls pass from the 40 chute C⁶ into the pockets. The chutes B⁶ and B⁷ are filled with balls, as shown, and a ball is contained within each guide-tube C and rests on one of the arms J' of the spider-wheel J, as shown in Fig. 5. One box-link D projects from the front side of the front guide- 45 roller D' and contains a cigar. The coin deposited slides down the coin-chute H, drops into the funnel H', and strikes upon the curved end I' of the lever I, whereby said curved end 50 of the lever is depressed, permitting the coin to pass and slide down the chute H H' into the coin-drawer H³. As the curved end I' of the lever I descends under the action of the weight of the coin, the toe I² on the opposite end is 55 raised, whereby the toe I² is disengaged from a pin I³, permitting the weight of the ball in the upper end of the guide-tube C to rotate the spider-wheel J in the direction of the arrow x³, Fig. 5. The inner end of the lever I immediately drops, catches on another pin I³, 60 thus preventing further rotation of said spider-wheel and disk in the direction of the arrow x³, and thus permitting only that ball that was in the upper end of the guide-tube C from passing down said guide-tube. A ball then immediately drops from the chute B' 65 into the guide-tube C, in which it is held by

the next fixed arm J' of the spider-wheel J in the position shown in Fig. 5. As said ball passes from the chute B' into the guide-tube C, all the remaining balls in the chutes B⁶ and B⁷ slide forward the distance of one ball. The ball that has been released from its position in the upper end of the tube C drops into the box C' and strikes the lower end of the arm F³, whereby the upper shank of the escapement-fork F' is disengaged from its tooth on the escapement-wheel F. At the same time the lower shank engages the tooth of the escapement-wheel. The ball then slides off the lower end of the arm F³, and the weight F⁴ draws down the shanks of the escapement-wheel, whereby the lower shank is disengaged from the escapement-wheel and the upper shank engages another tooth of said escapement-wheel. The escapement-wheel and the sprocket-roller D' have meanwhile been permitted to rotate the distance of one tooth of the escapement-wheel, which is equivalent to the distance of one side of the sprocket-roller. Thereby that box D² of the chain D that has projected horizontally from the front of the roller D' is brought in such position as to project downward diagonally from said roller, permitting the cigar to slide out of said box into the chute G, and from the same into the trough G'. The ball that has dropped into the box C', after it has acted upon the arm F³, rolls through the tube C² into the chute C⁸, down the same through the chutes C⁴ and C⁵, strikes the arms of the spider-wheels C⁷, and causing the wheel C⁹ to move, whose pins C⁹ strike the pawl C¹⁰, whereby the wheel B is released and rotated a distance of one pocket B' in the direction of the arrow x², Fig. 3, whereby a ball is released and passes into the chutes B⁶ and B⁷, and at the same time a fresh ball passes into one of the bottom pockets of the wheel B'. Every time a nickel is dropped or deposited a ball passes out of one of the pockets of the wheel, operates the device for releasing a chain, and then passes back into one of the pockets, it being immaterial whether said coin was dropped in the first, second, or third coin-chute. If the coin is dropped in the first coin-chute only, the balls in that part of the chutes B⁶ and B⁷ between the wheel B and the first guide-tube C will roll forward. In case the coin is dropped in the second coin-chute, all the balls in the chutes B⁶ and B⁷ between the second guide-tube C and the wheel B move forward, and in case the coin is dropped in the third coin-chute all the balls in the chutes B⁶ and B⁷ between the third guide-tube C and the wheel B move forward. As stated, the lever I descends after a coin has passed the curved end I' of said lever, and thus locks the disk I⁴ in place after the same and the spider-wheel J have turned sufficiently to permit one ball to pass out of the guide-tube C. This holds good when the pins I³ are arranged singly on the rim of the disk I⁴, but not when they are arranged in groups of two, three, or

more. For example, if the pins were arranged in groups of two, the descending coin would disengage the toe I^2 from the first pin, but said toe would immediately engage the following pin, and thus also the disk I^4 , the spider-wheel J thereby locking them before the ball in the tube C is released. For releasing said ball, two coins must be dropped successively into the coin-chute, so that the lever I will be operated twice and the toe I^2 also disengaged from the second pin, when the wheel J can rotate sufficiently to release the ball in the tube C . In case the pins on the disk I^4 are arranged in groups of three, three coins must be dropped successively, and so on.

If the different articles in the box-links of the different chains are to be sold for the same amount—that is, a single coin of a certain value—the pins I^3 on all the disks I^4 can be arranged singly; but if the articles in the box-links of a certain chain are to be sold for two coins the pins I^3 on the corresponding disk I^4 must be arranged in groups of two.

In place of cigars, packages of cigarettes, chewing-gum, candies, chocolate, ferry-tickets, fruits, or various articles can be placed into the box-links, which must have corresponding sizes.

Having thus described my invention, I claim as new and desire to secure by Letters Patent—

1. In an automatic selling-machine, the combination, with a ball-elevator and a motor for operating the same, of one or more independent box-link chains for receiving the articles to be delivered by the machine, motors for moving said box-link chains, and retaining devices for the said motors of the box-link chains, which retaining devices are to be operated by the balls raised by the ball-elevator, substantially as herein shown and described.

2. In an automatic selling-machine, the combination, with a ball-elevator and a motor for the same, of a box-link chain for receiving the articles to be delivered by the machine, a motor for moving said chain, a retaining device for said motor, and a coin-operated ball-retainer, substantially as herein shown and described.

3. In an automatic selling-machine, the combination, with a ball-elevator and a motor for the same, of a chute into which the balls can pass from the ball-elevator, a ball-outlet tube on said chute, a coin-operated ball-retainer, a box-link chain for receiving the articles to be delivered by the machine, a motor for said chain, and a chain-motor retainer operated by the balls released by the coin-operated ball-retainer, substantially as herein shown and described.

4. In an automatic selling-machine, the combination, with a ball-elevator and a motor for the same, of a chute into which the balls pass from the ball-elevator, an outlet-tube for the balls on said chute, a coin operated ball-retainer at said outlet-tube, a box below said outlet-tube, a box-link chain for receiving the

articles to be delivered by the machine, a motor for said chain, and a retaining-lever for said motor, the ends of said retaining-lever projecting into the box below the ball-outlet tube on the above-mentioned chute, substantially as herein shown and described.

5. In an automatic selling-machine, the combination, with a ball-elevator and a motor for the same, of a chute into which the balls can pass from the ball-elevator, a box-link chain for receiving the articles to be delivered by the machine, a motor for said chain, a retaining-lever for said motor, which lever is in the path of the dropping balls, and a chute for conveying the dropped balls back to the ball-elevator, substantially as herein shown and described.

6. In an automatic selling-machine, the combination, with a box-link chain for receiving the articles to be delivered by the machine, of a series of sprocket-wheels over which said chain passes, a rope-drum on one sprocket-wheel, a rope and weight connected with said drum, an escapement-wheel on said sprocket-wheel, an escapement-fork engaged with said escapement-wheel, and a ball-elevator for elevating balls to operate said escapement-lever, substantially as herein shown and described.

7. In an automatic selling-machine, the combination, with a ball-elevator and a motor for the same, of a chute into which the balls can pass, a series of ball-outlet tubes on said chute, a spider-wheel at each outlet-tube, levers for locking the spider-wheels, coin-chutes into which said levers project, box-link chains for receiving the articles to be delivered, motors for operating the chains, and retaining-levers for said motors, which retaining-levers are operated by the balls as they drop from the guide-tubes of the chute, substantially as herein shown and described.

8. In an automatic selling-machine, the combination, with a chute, of an outlet-tube, a spider-wheel projecting into the outlet-tube, a disk on the same shaft with the spider-wheel with pins arranged singly or in groups, and a coin-actuated lever engaging said pins, substantially as herein shown and described.

9. In an automatic selling-machine, the combination, with a ball-chute, of an outlet-tube on the same, a spider-wheel projecting through a slot of said outlet-tube, a disk secured on a sleeve mounted to slide on and turn with the shaft of the spider-wheel and having pins arranged singly and in groups in different circumferential rows on its rim, and a coin-actuated lever engaging said pins, substantially as herein shown and described.

10. In an automatic selling-machine, a mouth-piece for a coin-chute constructed with a casing having an opening in its top plate, sliding spring-actuated jaws in said top plate, and a spring-actuated gate hinged below said top plate, substantially as herein shown and described.

11. In an automatic selling-machine, a

mouth-piece for a coin-chute constructed with a casing having an opening in its top plate, beveled sliding springs, actuated jaws in the edges of said plate, which jaws have bevels 5 on their top and bottom edges, and a spring-actuated gate below said top plate, substantially as herein shown and described.

In testimony that I claim the foregoing as my invention I have signed my name in presence of two subscribing witnesses.

JOHN W. VAUGHN.
